UNITED STATES PATENT OFFICE.

DAVID W. PATTON, OF MOBERLY, MISSOURI, ASSIGNOR OF ONE-HALF TO TONY R. FIORITA, OF MOBERLY, MISSOURI.

INJECTOR.

1,120,526.

Specification of Letters Patent.

Patented Dec. 8, 1914.

Application filed June 25, 1914. Serial No. 847,269.

To all whom it may concern:

Be it known that I, DAVID W. PATTON, a citizen of the United States, residing at Moberly, in the county of Randolph and State 5 of Missouri, have invented certain new and useful Improvements in Injectors; and I do declare the following to be a full, clear, and exact description of the invention, such as will enable others skilled in the art to which 10 it appertains to make and use the same.

My invention relates to improvements in injectors and more particularly to the delivery tubes thereof.

The primary object of the invention is to 15 provide a device of this character so constructed as to reduce the amount of wear upon the tube by the jet of water forced therethrough and to provide means whereby this jet of water may be broken into a fine 20 mist thereby allowing the same to be more readily heated upon entrance to the boiler.

A secondary object of the invention is to make the above set forth improvements without the necessity of altering other parts 25 of the form of injector with which the invention coöperates.

With these objects in view, the invention resides in certain novel features of construction and combination herein described and 30 claimed and shown in the drawings wherein:

Figure 1 is a vertical section through a portion of what is known as a Sellers' injector, showing the application of my improved delivery tube thereto; and Fig. 2 is 35 an end view of the tube removed from the injector.

In the accompanying drawings I have shown portions of an injector I which is of common construction being provided with 40 the usual steam and water inlets (not shown) and a water outlet O. The interior of the casing, directly above the outlet O, is provided with a threaded bore B in which an externally threaded portion 1 of the delivery

45 tube 2 is located, the threads of the portion 1 engaging the threads of the bore B. In applying my improvements to the delivery tube 2, no alteration whatever is made to the exterior thereof. The passageway 3 of 50 said delivery tube, however, is formed of a plurality of bores indicated in the drawings at 4, 5, 6 and 7, said bores increasing in diameter from the innermost bore 4 to the outermost bore 7 while each one of said bores in-

creases in diameter from its inner to its 55 outer end. By this formation, a number of annular shoulders 8 are formed over which the jet of water must flow while passing through the passageway 3, thus effectually reducing the jet of water to a fine mist or 60 spray before the same enters the boiler. It will be evident that the wear of the spray against the walls of the various bores is considerably less than would be the wear of an uninterrupted jet of water passing directly 65 through a smooth bore. The water is therefore allowed to pass more quickly through the injector and into the boiler and is also in such condition as to be quickly and easily heated upon entrance to said boiler, these 70 two features being extremely important and greatly prolonging the life and efficiency of the injectors to which the invention is applied.

As shown in the drawings, a circulating 75 tube T may be employed in connection with my improved delivery tube, the inner end of said tube being threaded in an opening o which is formed longitudinally through the portion 1 of the tube 2, while its outer end 80 lies flush with the outer end of said tube. The provision of this circulating tube, allows any steam or air which may have collected in the casing of the injector to be readily expelled therefrom, thereby preventing the movement of the water from being retarded. For more detailed explanation of the functions of the tube T reference may be made to my United States Patent 1,000,548, patented Aug. 15, 1911, in which the circulating passages 15 perform identically the 85 same functions as the tube T in the present case.

It will be clearly understood that, although the circulating tube T increases the 95 efficiency of the injector, the delivery tube herein described might well be employed without this feature.

Having thus described my invention, what I claim as new and desire to secure by Letters Patent is:—

1. An injector having a water inlet, a water outlet, a threaded bore between the two, and an integral delivery tube having an externally threaded portion engaged with 105 the threads in said bore, the longitudinal passage in said tube increasing in diameter from its receiving end to its delivery end,

said passage abruptly increasing in diameter at a plurality of points spaced substantially equi-distantly.

2. An injector having a water inlet, a water outlet, a threaded bore between said inlet and outlet, and an integral delivery tube having its intermediate portion formed with an integral externally threaded enlargement, the threads of said enlargement being interengaged with the threads in said bore, the longitudinal passage through said tube increasing in diameter from its receiving

end to its discharge end, said passage abruptly increasing in diameter at a plurality of longitudinally and substantially equi-distantly spaced points. 15

In testimony whereof I have hereunto set my hand in presence of two subscribing witnesses.

DAVID W. PATTON.
